ENCIRCLING BAND TIGHTENER

Albert J. Scholtes, Baltimore, Md.

Application November 12, 1934, Serial No. 752,775

15 Claims. (Cl. 24—19)

The present invention relates to clamps for hose and the like, and has for an object to provide an improved and simplified construction of locking clamp wherein the band has a loop at one side and a loop expansion strip for feeding into the loop to enlarge it and contract the band, and wherein the expansion strip may be of any desired and practical length and fed to the interior of the loop wholly from the exterior of the band.

Another object is to provide a construction wherein the expansion strip may be rolled into the loop, and wherein means is provided for obtaining a double effect in enlarging the loop by the winding or rolling of the strip to secure "quick acting" clamping operation of the band and of the binding and anchoring of the free end of the band.

A further object is to provide the clamp with a loop plate which may be relatively short or small so that the clamp as a whole may be made relatively small and applied to small diameter hoses, pipes and the like.

Another object of the invention is to reduce the frictional contact of the rolling strip to a minimum so that it will reduce tension on the band and other part and will admit operation of the clamp with relatively small effort, and to provide a clamp wherein both the band and the rolling strip may be of any practical length and easily and quickly applied to the work from any convenient side thereof.

A further object of this invention is to provide a clamp with a band and a rolling strip which, during the clamping action, are drawn lengthwise in their respective directions of clamping and rolling to effectively lock the parts rigidly against backward movement and reduce the effort required in applying the clamp.

With the foregoing and other objects in view, the invention will be more fully described hereinafter, and will be more particularly pointed out in the claims appended hereto.

In the drawing, wherein like symbols refer to like or corresponding parts throughout the several views,

Figure 1 is a fragmentary perspective view of the adjustable and locking portions of the band tightener of this invention.

Figure 2 is an edge view of the band tightener showing the free end of the band threaded through the plate and ready for drawing into initially tight position.

Figure 3 is a similar view showing the band tightener as applied to an object and in a tightened and locked position.

Figure 4 is a detail perspective view of the tightener plate employed.

Figure 5 is a fragmentary perspective view of one end of the winding strip, showing a modified construction for attaching the strip to the winding member.

Figure 6 is a like view showing a further modification in the attaching means for the strip by the winding member.

Figure 7 is a detail perspective view of a modified form of winding member.

Figure 8 is a fragmentary perspective view of the loop and of the object encircling band, showing a slight modification maintaining the loop, and

Figure 9 is a fragmentary sectional view through a modified form of the band tightener.

Referring now to the drawing, the band tightener comprises a plate 10 or similar member for accomplishing the purposes of this invention.

Figure 4 shows a detail view of this plate and it will be noted that it is provided with a single opening 11 extending generally lengthwise of the plate and the plate has at one end of the opening 11 a shoulder 12 which may be constructed in any suitable manner such as by striking out a lug 13 or the like from the opening 11 and turning the lug outwardly of the plate so as to be disposed at the outer side of the tightener.

This lug 13 has its outer corner edge rounded as at 14 to provide a rounded and smooth surface over which one end of a band, later described, may be drawn tight. It will also be noted that the outer edge portion of the lug 13 is rounded or arched upwardly as at 15 for the purpose of holding the band in a substantially rounded or cup-shape as will appear later. The lug 13 is also provided intermediate its ends with an outwardly pressed rivet 16 which may be used for securing the adjacent end of the band thereto.

The plate 10 is provided at the other end of the opening 11 with a slightly upturned and transversely rounded lip 17 over which may be engaged the opposite end portion of the band for holding the latter against sliding movement.

The band tightener is provided with an object encircling band 18 which is of suitable dimensions to accommodate the work. One end of the band 18 extends through the opening 11 of the plate 10 from the inner to the outer side of the plate, and said end of the band 18 is lapped over against the outer side of the lug 13 and is suitably apertured for the reception of the rivet 16 therethrough, the rivet being upset or expanded against the outer side of the band to securely

attach the band to the lug. The band extends from the rivet 16 upwardly over the outer face of the lug 13, over the rounded or curved edge 14 of the lug, and also over the top or outer edge 15 of the lug, the latter bulging or bowing the band transversely outward to impart a substantially cup-shape to the band to hold the lateral edge portions thereof taut and from flaring. The end of the band which extends from the outer edge of the lug 13 forms a loop between the lug and the plate and this loop is of desired size so as to accommodate therein and against the lug 13 a suitable expanding device as hereinafter brought out. The band 18 is adapted to be placed about an object to which the tightening device is to be clamped. The free end 19 of the band is threaded through the opening 11 of the plate from the inner to the outer side thereof, and the band is drawn through the opening 11 into substantially tight position on the object and may then be bent over the lip 17 to any desired extent so that the lip, incident to its raised and transversely curved structure may frictionally engage with the band and effectively hold it from drawing through the opening 11 of the plate.

The loop 20 of the band is so disposed that the end of the band which extends into the loop 20 lies adjacent to the end 19 of the band so that as the loop 20 is enlarged and drawn outwardly from the plate the movement is in the general direction of drawing the end 19 taut and thus the formation and enlargement of the loop maintains and locks the free end 19 of the band effectively to the plate.

The means for expanding the loop 20 may be a winding strip 21 which is disposed wholly without the band 18 and is introduced at one end beneath the plate 10 against the outer side of the secured end of the band 18, as shown in Figures 2 and 3, and this strip 21 extends along the outer surface of the band and into the loop 20 and lies against the inner side of the loop and against the inner side of the lug 13. A transverse winding member 22, which may be a cotter key or pin, as shown in Figures 1, 2 and 3, is disposed transversely in the loop 20 and is engaged with the end of the winding strip 21. By turning the cotter key 22 the end of the strip 21 is wound about the shank of the cotter key and also wound upon itself into successive layers which gradually expand or increase the size of the expanding device so that the expanding device works against the inner side of the loop 20 at one side of the axis of the key 22 and also works against the inner side of the lug 13 at the opposite side of the axis of the key 22. As the lug or shoulder 13, or 12, is stationary, and as the loop 20 is expandable, the piling up of the successive layers of the strip 21 on the winding device or roll effects a double quick action on the expansion of the loop 20 as the axis of the winding device is gradually shifted from the shoulder 12 to enlarge the loop, and additionally the loop is enlarged by the successive layers of the strip 21 as they are brought between the axis of the pin and the inner side of the loop 20.

It is apparent that the winding strip 21 may be of any length within practical limits as the latter lies outside of the band 18, and further the strip 21 has no frictional contact with the object clamped and is so located that the frictional contact of the strip 21 with the band 18 and loop 20 is such as to insure the tension of the parts when drawn taut and also insures the relatively easy

operation of the winding of the strip with the least resistance.

From Figure 3, it will be noted that as the winding device feeds the strip 21 into the loop 20, the latter is enlarged by drawing successive portions of the band outwardly through the opening 11 of the plate, and these successive portions of the band 18 are drawn and held tight against the free end 19 of the band 18 at a point opposite the lip 17 so as to bind the band to the lip by the pressure of the loop 20. It will be noted from Figure 3 that the lip 17 is upturned at a suitable angle to present a substantial surface portion of the end 19 of the band against the base part of the loop 20.

It may be here noted that the transverse curvature of the edge 15 on the outer end of the lug 13 holds the roll or winding device within the loop 20 and maintains the same from edgewise or lateral displacement in either direction therefrom.

Referring now to the modification shown in Figure 5, the winding device 23 is shown in the form of a one-piece shank or pin having an apertured head 24 on its end by means of which the shank 23 may be turned. The shank 23 is provided in its side with an outwardly extending lug or stud 25. The winding strip 26, similar to the strip 21 above described, may be provided with an aperture 27 near its free end adapted to receive therein the stud or projection 25 for anchoring the strip 26 to the shank 23 when the strip is rolled thereon.

In Figure 6, there is shown another slight modification wherein the cotter key 28 may receive the strip 26 between the arms thereof and one of the arms of the cotter key is provided with a stud or projection 29 adapted to fit in the opening 27 of the winding strip. In this instance the stud 29 and the opening 27 co-act to hold the cotter key 28 from sliding lengthwise out of the roll.

From the drawing it will be noted that the plate 10 may be longitudinally rounded or be given an arcuate shape to more readily conform to the objects to which the band tightener may be applied.

In use, the band 18 may be wrapped about an object from any convenient side thereof and the free end 19 of the band threaded through the opening 11 of the plate and bent back over the tongue 17. The end 19 is drawn initially taut. The winding device 22 is now turned in such direction as to draw the winding strip 21 inwardly between the plate 10 and the outer side of the band 18, the strip 21 being wound in successive layers upon the pin and upon itself to gradually enlarge or expand the loop 20 and contract the band 18. As the loop is enlarged sufficiently to begin the tightening and clamping action the loop is brought against the overturned end of the band which rests on the lip 17 and thus the band is firmly held from slipping on the object. The winding device 22 may be turned up to any desired extent so as to obtain the desired clamping action of the band 18 on the object. As soon as the winding device 22 is released, there is no danger of the tightener being released as the winding device is self locking and the tension exerted by the clamping action merely more effectively binds the adjacent end portions of the band at the lip 17, and there is no drawing or reverse turning forces to unwind the strip 21. The strip 21 lies in frictional contact with the outer side of the band 18 beneath the adjacent

end of the plate 10 and also lies in frictional contact throughout a substantial portion of the loop 20.

The shoulder 12 also binds against one side of the roll so as to further hold the latter frictionally against retrograde turning movement.

It will be noted that the clamp can only be removed by breakage or destruction of the band 18 because the winding strip 21 cannot be unwound 10 or drawn out of the loop.

It will be noted that the lateral portions 30 of the plate, lying at opposite sides of the opening 11, are forced into close sealing engagement with the object, as shown in Figure 3, in register with the slight gap 31 which may appear between the meeting ends of the band 18 beneath the lip 17. Thus the side portion 30 effectually seal the band tightener on the object at this point of juncture of the ends of the band.

20 During the winding action of the strip 21 the roll is enlarged and advanced in the direction lengthwise of the plate 10 from the shoulder 12 and consequently effects a substantially longitudinal drawing action on the band through the opening 11 of the plate and quickly moves the loop 20 into contact with the end 19 of the band to hold the latter from slipping during subsequent binding action. This movement also imparts a double feed action for the loop 20 as the roll is advanced against the shoulder 12 at the same rate as the roll is advanced against the outer side 30 of the loop 20.

The winding or rolling element or member may be of the form shown in Figure 7 wherein the shank 32 with its head 33 may be of the construction of a cotter pin to receive the portion of the winding strip, and wherein the free ends of the shank 32 are curved or bent outwardly from each other to provide flaring lips 34 which serve 40 as guides to engage and direct the edge portion of the winding strip into the slot between the shank sections. Further, these lips 34 also serve as shoulders to prevent the shank 32 from being withdrawn from the roll when the latter is formed in the winding member, and has the same effect as the projections 25 and 29 with their strip openings 27 shown in Figures 5 and 6. The projection 25 has the additional function of holding the winding strip from lengthwise turning on the shank 23.

50 In Figure 8, the object encircling band 35, which may be substituted in any of the forms of the band tightener shown in the drawing, has a widened loop portion 36 presenting shoulders 37 at opposite ends adapted to engage the outer face of the plate 10 at the side portions 30 to hold the loop from withdrawal through the plate particularly when the parts are assembled and during the preliminary tightening of the device.

60 As one of the various modifications which may be resorted to in carrying out the features of the present invention, Figure 9 shows the object encircling band 38 as having the loop portion 36 of Figure 8 therein and in position through the opening 11 of the plate 10, the free end of the loop portion 36 being riveted at 39 directly against the underside of the plate 10. The other end of the band 38 has a winding strip portion 40 associated therewith and, as shown in the present instance, may comprise an extension or elongation of the band 38 which passes out through the opening 11 of the plate 10 into the loop 36 and is engaged through the split key or winding element 32, the extremity being carried from the 70 key 32 backwardly out of the loop 36 through the

opening 11 and from beneath the plate 10 as shown. The winding element 32 may be turned in either direction for winding or rolling in double thickness the returned strip end 40 of the band thereon and within the loop 36. The forming of the roll on the element 32 binds the roll against the lug 13 and also binds the roll against the band 38 where it passes over the lip 17.

What is claimed is:—

1. A band tightener, comprising a plate having an opening therein, a band extending through the opening with one end secured to the plate and looped outwardly therefrom to form a loop at the outer side of the plate, the other end of the band adapted to encircle an object, and expanding means including a winding strip disposed in the looped portion of the band with the free end of the strip extending through the opening in the plate between the latter and the outer side of the band. 20

2. A band tightener, comprising a plate with an opening therethrough, an object encircling band having both ends extending through the opening in the plate and with one end looped outwardly from the plate and against the other end of the band to bind the latter to the plate and with the first end secured to the plate at the end of the loop, and expanding means in the loop and including a winding strip passing through the opening between the plate and the outer side of the band. 25

3. A band tightener, comprising a band, a plate having an opening therein and a lug struck up from one end of the opening, one end of said band secured to said lug and looped therefrom through the opening and adapted at its free end to encircle an object to be clamped, the free extremity of the band adapted to be returned through said opening and turned over on said plate, a rolling member disposed transversely 40 through the looped portion of the band, and a rolling strip extending at one end through the opening in the plate between the latter and the outer side of the band and into said loop portion of the band and connected to said rolling member, whereby turning of the rolling member winds the strip thereon and against said loop portion of the band and the fixed lug of the plate to expand the loop portion by direct pressure of the rolled strip thereagainst and against the fixed 50 lug. 45

4. A band tightener, comprising a plate having a single opening therethrough and a lug struck outwardly at one end of the opening to provide a shoulder on the plate, a band having one end attached to the lug and looped outwardly therefrom and extending through the opening to provide a loop at the outer side of the plate, the free end portion of the band adapted to encircle an object and for adjustable attachment to the plate and expanding means in the loop including a rolling strip adapted to be wound upon itself for impinging the shoulder of the plate at one side of the expanding means and for engaging the loop of the band at the opposite side of the 65 expanding means to effect a double expansion action on the loop and the quick contraction of the band on the object. 60

5. A band tightener, comprising a plate having an opening therein, a band secured at one end to the plate near one end of the opening and looped outwardly from the plate and extending inwardly through the opening, said band adapted for passage about an object to be clamped and with its other end passing outwardly through 70 75

the opening in the plate against the outer side of the looped portion of the band, an expanding strip having one end extending through the plate opening between the plate and the outer side of the band and into said looped portion of the band, and feeding means engaging the strip to force the same through the opening into the looped portion to expand the same and contract the band on the object and bind the looped portion against the said other end of the band to anchor the same to the plate.

6. A band tightener, comprising a plate having an opening therethrough, an object encircling band having its ends extending through the plate at one end of the opening, one end of the band being looped backwardly and attached to the plate near the other end of the opening, a winding device disposed transversely in the loop of the band, and a winding strip having one end lying between the plate and the outer side of said end of the band and extending against and with the latter into said loop and engaging the winding device, thereby to facilitate the winding of the strip upon itself and to expand the loop with a retaining movement against the other end of the band in the plate opening.

7. A band tightener, comprising a plate having an opening therethrough, an object encircling band having one end for adjustable attachment to the plate and having its other end extending outwardly through the opening in the plate and looped over and secured to the plate, a winding strip having one end passing between the plate and the outer side of the band through the plate opening and into the loop, and winding means for winding the end of the strip upon itself within the loop to expand the same and contract the band on the object, said winding means being operable in a direction to feed the strip into the loop against and in the direction of movement of the adjacent end portion of the band, thereby to facilitate operation of the winding means.

8. A band tightener, comprising a band, a plate having an opening therein and a shoulder at one end of the opening, said band being anchored at one end to the plate adjacent the shoulder and being looped therefrom through the opening of the plate and disposed about an object to be clamped and having its other end turned over through the opening in the plate, a loop expanding strip having one end introduced through the opening of the plate into the looped portion of the band between the band and the plate, and expanding means cooperating with the strip for feeding the strip into the looped portion of the band against the latter and against the said shoulder of the plate.

9. A band tightener, comprising a plate with an opening therethrough, an object encircling band having one end extending outwardly through the opening in the plate to form a loop at the outer side of the plate and secured to the latter at the end of the loop and the other end of the band adapted for adjustable engagement with the plate, and expanding means in the loop and including a strip extending inwardly through the opening between the plate and the outer side of the band.

10. A band tightener, comprising a plate with an opening therethrough, a band having one end looped through the opening of the plate and se-

cured thereto at the end of the loop, and expanding means in said loop to enlarge the same and contract the band, and including a strip with its free end extending from within the loop at the outer side of the band.

11. A band tightener, comprising a plate having an opening therethrough providing flat side portions at opposite sides of the opening, an object encircling band having one end looped upwardly through said opening, and secured to the plate at the end of the loop, the band having its other end extending upwardly through the opening against the first end of the band, and winding means disposed in the loop of the band at the upper side of the plate for enlarging the loop and contracting the band on the object, said loop adapted to bind against said opposite end of the band to hold the same to the plate, said portions of the plate at the opposite sides of the opening therein adapted to seal and bind against the object across the gap between the meeting ends of the band in the opening.

12. A band tightener, comprising a plate with an opening therethrough, an object encircling band having one end looped through the opening of the plate and secured thereto at the end of the loop, a winding strip portion associated with one end of the band and adapted at one portion to enter the loop and having its free end disposed exteriorly of the band, and means for rolling the said winding strip portion into an expanding roll within the loop, thereby to enlarge the loop and contract the band on an object.

13. A band tightener, comprising a plate with an opening therethrough, an object encircling band having one end looped through the opening of the plate and secured thereto at the end of the loop and having its free end projecting through the opening in the plate and into the loop, a winding means within the loop and adjustably connected to said free end for winding the band upon itself to form an expanding roll within the loop for tightening the band.

14. A band tightener, comprising a plate with an opening therethrough, an object encircling band having a portion looped through and secured to the plate and having its free end projecting through the opening in the plate and into the loop, a winding means within the loop and adjustably connected to said free end for winding the band upon itself to form an expanding roll for tightening the band.

15. A band tightener comprising a plate with an opening therethrough and a lug struck up from one end of the opening, an object encircling band having a portion looped through the plate and having one end secured to the plate and its free end adapted to encircle an object and to extend through the opening in the plate within the loop, a winding means disposed transversely through the looped portion of the band and adjustably secured to said free end of the band, whereby turning of the winding means winds the band upon itself into an expanding roll and against said loop forcing one side of the loop against the lug of the plate and frictionally locking said winding means from retrograde turning movement when the band has been tightened about an object.
